UNITED STATES PATENT OFFICE.

JAMES B. REPLOGLE, OF CHICAGO, ILLINOIS.

APPARATUS FOR DETERMINING WORKING-SPACE.

1,151,716.

Specification of Letters Patent. Patented Aug. 31, 1915.

Application filed November 28, 1913. Serial No. 803,412.

To all whom it may concern:

Be it known that I, JAMES B. REPLOGLE, citizen of the United States, residing at Chicago, in the county of Cook and State of Illinois, have invented a certain new and useful Improvement in Apparatus for Determining Working-Space, of which the following is a full, clear, concise, and exact description, reference being had to the accompanying drawings, forming a part of this specification.

My invention relates to apparatus for ascertaining the working space which intervenes between objects that exert heavy working-like compressing pressure upon a third object interposed between the aforesaid objects and is of particular service in measuring the working space intervening between the cylinders and beds of printing presses.

The method involved in the use of the apparatus consists in yieldingly maintaining heavy separating working-like pressure upon the objects that exert the compressing pressure and measuring the resulting space existing between these objects.

In the apparatus of my invention I employ a follow-up pressure contact device which is adapted to keep in simultaneous engagement with the cylinder and bed or other compressing objects and to maintain heavy separating working-like pressure thereupon irrespective of the variations in the spacing and whether or not such spacing exceeds or is less than the spacing normally occupied by the printing form or other interposed object of correct height.

The invention has other features and advantages and will be more fully explained by reference to the accompanying drawings showing the preferred embodiment of the invention, and in which drawings—

Figure 1 is a sectional view on line 1 1 of Fig. 3; Fig. 2 is a sectional view on line 2 2 of Fig. 1; Fig. 3 is a plan view of the equipment as exhibited in Figs. 1 and 2; Fig. 4 is a view of the apparatus of my invention on a larger scale, its association with a printing cylinder and form bed being diagrammatically indicated; Fig. 5 is a plan view of the instrument of my invention; Fig. 6 is a sectional view on line 6 6 of Fig. 4; Fig. 7 is a sectional view on line 7 7 of Fig. 4; Fig. 8 is a rear view illustrating the multiplying gearing of one form of metric gage and parts coöperating with such gearing; and Fig. 9 is a reverse view of the

structure shown in Fig. 8 except that the dial there illustrated conceals the gearing.

Like parts are indicated by similar characters of reference throughout the different figures.

The invention has been applied to printing presses for the purpose of ascertaining the working space which intervenes between the press bed and the complementary compression element respectively indicated in the drawings at *a*, *b* where *b* represents the rotating tympan or printing cylinder of a cylinder press. As the invention is adaptable to various printing presses it will be unnecessary to describe the mechanism of any particular press to which the invention is adaptable. The elements *a* and *b* thus constitute two objects that exert heavy working-like compressing pressure upon a third object, namely the printing form, interposed between the aforesaid objects and between which aforesaid objects the working space is to be ascertained. The spacing which intervenes between the press bed and the cylinder, before such spacing has been corrected by the pressman as by changing the thickness of the cylinder packing or by underlaying the form, is, as a most usual occurrence, non-uniform, this spacing sometimes happening to be type high in some places and in other places exceeding or being less than this type high dimension. I employ a device, which is desirably in the form of a very heavy and powerful U-shaped spring *c* which constitutes a yielding follow-up contact device whose resilience is such that it will spread apart at its free ends, when not subject to material counteracting pressure, to an extent which will exceed the maximum spacing which is likely to intervene between the cylinder and bed. In practice I have found that one-tenth of an inch is sufficient for the follow-up contact device *c* to spread at its free ends in excess of the type high dimension. The top and bottom faces of the free ends of the arms of the loop *c* are accurately planed so as to be flat and practically parallel in the type high position of the loop and so relatively positioned that they will be separated one-tenth of an inch in excess of the type high dimension when relieved of extraneous pressure. It is preferable to employ a plurality of closely approached follow-up contact springs or pressure devices *c* (Figs. 2 and 3) each in the position described to ap-

proach working conditions as much as possible. Each follow-up pressure or spring device *c* is adapted yieldingly to maintain heavy separating working-like pressure 5 upon the printing bed and cylinder, such pressure being obviously substantially constant throughout the range of relative movement of the engaged surfaces of the follow-up pressure device. The cylinder and bed 10 thus exert heavy working-like compressing pressure upon the follow-up pressure contact devices *c* since these devices yieldingly oppose similar counteracting separating pressure upon the bed and cylinder. If 15 space in excess of type high dimension is being measured it will be apparent that the measuring device *c* located in such space will follow the cylinder so as to fill such space while maintaining heavy working-like 20 separating pressure upon the cylinder and bed to enable the proper measurement of the space, the measuring device *c* thus being distinguished from the type high printing form which is incapable of thus adapting 25 its height to the larger spaces so frequently initially intervening between bed and cylinder. An important feature of my invention, therefore, consists in yieldingly maintaining, during the measuring operation, 30 heavy separating working-like pressure upon the objects which exert heavy working-like compressing pressure upon a normally interposed object, the follow-up contact pressure device *c* thus constituting an 35 object temporarily interposed, for the purpose of measurement, between the compressing objects, which temporarily interposed object automatically adapts itself to the spacing between the compressing objects 40 while at the same time yieldingly maintaining heavy separating working-like pressure upon the compressing objects irrespective of the spacing intervening between such objects within the limits of the measuring 45 device.

The distance intervening between the top and bottom engaged faces of each interposed measuring device *c* is the measure of the spacing there existing. In the apparatus of 50 the invention the follow-up pressure contact device *c* is desirably supplemented by a micrometric gage which is preferably in separable relation with the follow-up pressure contact device so that one gage may be 55 interchangeably associated with a plurality of the measuring devices *c* to avoid expense. In the preferred form of device the micrometric gage includes a pair of tongues *d* *e* centrally pivoted together at *f*, these tongues 60 being rounded at their free ends readily to be slipped within accurately formed recesses in the free ends of each instrument *c* which are thus caused to constitute jaws 65 which operate to cause the free ends of the tongues *d* *e* relatively to approach when these

jaws are approached and permitting these free ends of the tongues to separate when said jaws separate, the tongues *d* and *e*, and more particularly the tongue *e*, constituting followers which accompany the jaws of the 70 instrument *c* to which the tongues are applied. The rear end of the tongue *d* is enlarged to constitute a mounting *g* which supports a stop *h* to limit the extent to which the free ends of the tongues may be spread 75 apart when the micrometric gage is not in association with a measuring element *c*. The indicating mechanism of the micrometric gage is of any suitable form, that shown being supported upon the mounting 80 *g* and including the vertically disposed plunger *i* carrying an abutment *k* and pressed downwardly by a light spring *l* whereby this abutment *k* will maintain contact with the rear end of the tongue *e* irrespective of the relative positions of the tongues *d* and *e*. The pressure of the spring 85 *l* is so light as to have no discernible effect upon the measuring device *c*. For instance the pressure of the light spring in the device 90 as shown is one ounce whereas the pressure exerted by each measuring device *c* is five hundred pounds. The upper portion of the plunger *i* carries a rack *m* which constitutes an actuating element of a multiplying train 95 of gears *n*, the shaft of whose final pinion *o* carries an indicating needle *p*. The gage dial is carried by a ring *q* which may be turned to adjust the normal, idle or initial 100 position of the needle *p* with respect to the 100 dial. In using the device it is customary to compare the actual working space with a standard working space, to which end the 105 distance between the top and bottom engaging points of the left hand ends of the 105 tongues *d* and *e* are spaced apart a distance equaling a distance separating these engaging points when received within the jaws of the measuring element *c* whose engaging 110 faces are spaced apart a type high distance, 110 whereafter the dial ring *q* is adjusted to bring the zero mark of the dial scale into 115 register with the indicating end of the indicator needle *p*. After the micrometric gage has thus been adjusted it is adapted for interchangeability association (Figs. 2 and 3) 120 with the elements *c* then to measure the varying space between the bed and cylinder. Owing to the light spring *l* the follower *h* will maintain engagement with the rear end 125 of the tongue *e* whose position varies according to the spacing between bed and cylinder, the extent of the departure of this spacing from the standard working spacing being indicated by the departure of the needle *p* 125 from its zero or normal position ascertained above.

The scale divisions desirably represent each a thousandth of an inch, the multiplying gearing between the rack bar *m* and the 130

indicator p permitting of the large scale divisions indicated (Fig. 9). For example, if the spacing being measured should lack, say, five one-thousandths of an inch of the standard spacing the indicating needle p will come to rest five scale divisions in a clockwise direction from normal. If the spacing being measured should exceed the standard spacing by, say, ten-one-thousandths of an 10 inch the indicating needle p will come to rest ten scale divisions in a counter-clockwise direction from normal.

While I have herein shown and particularly described a specific form of the apparatus of my invention and one way of practising the method of the invention, I do not wish to be limited to the various details specifically set forth, but

Having thus described my invention I 20 claim as new and desire to secure by Letters Patent the following:—

1. A device for ascertaining the working space which intervenes between objects that exert heavy working compressing pressure 25 upon a third object interposed between the aforesaid objects, said device including a yielding element of changeable size for main-

taining heavy separating working-like pressure upon the compressing objects; and a measuring instrument including a gear operated indicator, a follower in controlling relation to the operating gearing of the indicator and whose position in turn is controlled by the element of changeable size interposed between the compressing elements. 30 35

2. A device for ascertaining the working space which intervenes between objects that exert heavy working compressing pressure upon a third object interposed between the aforesaid objects, said device including 40 yielding means for maintaining heavy separating working-like pressure upon the compressing objects; and a measuring instrument having a gear operated measuring element whose operating gearing is actuated by 45 the aforesaid means.

In witness whereof, I hereunto subscribe my name this twenty-sixth day of November, A. D. 1913.

JAMES B. REPLOGLE.
